DESIGN FOR AN EYESHIELD OR SIMILAR ARTICLE

Edward M. Splaine, Southbridge, Mass., assignor to American Optical Company, Southbridge, Mass., a voluntary association of Massachusetts

Application December 15, 1944, Serial No. 116,914

Term of patent 14 years

(Cl. D57—1)

To all whom it may concern:

Be it known that I, Edward M. Splaine, a citizen of the United States of America, residing at Southbridge, in the county of Worcester and State of Massachusetts, have invented a new, original, and ornamental Design for an Eyeshield or Similar Article, of which the following is a specification, reference being made to the accompanying drawing forming a part thereof.

Fig. 1 is a front elevational view of an eyeshield showing my new design;

Fig. 2 is a top plan view of the eyeshield shown in Fig. 1.

The characteristic features of my design are shown in full lines in the drawing.

I claim:

The ornamental design for an eyeshield or similar article, substantially as shown and described.

EDWARD M. SPLAINE.
